UNITED STATES PATENT OFFICE.

MARVEN WILLIAM CROW, OF FORT DODGE, IOWA.

PIPE WRENCH.

Application filed June 19, 1926. Serial No. 117,156.

This invention relates to a pipe wrench, to receive the plate when the shank 8 is
the general object of the invention being to
provide means whereby the jaws of the
wrench will automatically grip an object
placed between them in such a manner that
5 the more pull exerted on the wrench, the
tighter the wrench will grip the object.

Another object of the invention is to make
one jaw of the wrench in the form of a
10 rotary disk having teeth thereon, this disk also
acting to adjust the movable jaw.

This invention also consists in certain
other features of construction and in the
combination and arrangement of the several
15 parts, to be hereinafter fully described, il-
lustrated in the accompanying drawings, and
specifically pointed out in the appended
claim.

In describing my invention in detail, ref-
20 erence will be had to the accompanying
drawings, wherein like characters denote
like or corresponding parts throughout the
several views, and in which:—

Fig. 1 is an elevation of the improved
25 wrench,
Fig. 2 is an edge view thereof,
Fig. 3 is a section on line 3—3 of Fig. 2,
Fig. 4 is a section on line 4—4 of Fig. 1,
and Fig. 5 shows a section on line 5—5 of
30 Fig. 1.

In these views, 1 indicates the handle of
a wrench which is formed with an enlarged
inner end 2 which is provided with a recess
3 which opens out through a corner of said
35 end. A U-shaped frame 4 is fastened to
this enlarged end by the bolts 5 and 6, the
bolt 6 forming a bearing for a toothed disk
or wheel 7 which is arranged in the recess.
This frame forms a guide for the shank 8
40 of the movable jaw 9, said shank being pro-
vided with the teeth 10 on its inner edge,
which are engaged by the teeth of the disk,
and the jaw 9 is provided with the gripping
teeth 11. A plate 12 is pressed against a
45 part of the teeth of the shank 8 by means
of a coiled spring 13 arranged in a recess 14
in the part 2, the plate having a stem 15
thereon which extends into the recess and
around which the spring is placed. The
50 part 2 is formed with a shallow recess 16

From the foregoing, it will be seen that
when a pipe or other object is seized by the
wrench, the entrance of the object between
55 the jaws will cause the rotation of the wheel
or disk 7, and the movement of this disk is
communicated to the shank 8 through the
teeth 10 so that the jaw 9 will be moved
inwardly to engage the object. Thus the
60 object is automatically gripped by the plac-
ing of the wrench thereon and the force
exerted on the wrench to turn the pipe or
object will cause the wrench to more firmly
65 grip the object.

The spring-pressed plate 12 acts to hold
the movable jaw 9 against the object, though
by pressing the inner end of the shank 8
downwardly to force the plate 12 in its
70 recess, the movable jaw can be readily ad-
justed to enable the wrench to fit various
sizes of objects.

It is thought from the foregoing descrip-
tion that the advantages and novel features
of my invention will be readily apparent.
75

I desire it to be understood that I may
make changes in the construction and in the
combination and arrangement of the several
parts, provided that such changes fall within
80 the scope of the appended claim.

What I claim is:—

A wrench of the class described comprising
85 a handle having an enlarged inner end
which is provided with a recess, a yoke-
shaped frame fastened to the enlarged por-
tion and having a part forming a guide, a
movable jaw having a shank slidably mount-
ed in the guide, the inner edge of the shank
being toothed, a toothed wheel rotatably
mounted in the recess with its teeth engag-
ing the teeth of the shank and some of its
teeth projecting beyond the end of the en-
larged part so that they will engage and be
placed between the jaws and thus the wheel
will be rotated, and a spring-pressed plate
90 carried by the handle and engaging the
shank.

In testimony whereof I affix my signature.

MARVEN WILLIAM CROW.
